UNITED STATES PATENT OFFICE.

DAVID B. KERR, OF PHILADELPHIA, PENNSYLVANIA.

DESIGN FOR AN UPHOLSTERY FABRIC.

SPECIFICATION forming part of Design No. 13,908, dated May 15, 1883.

Application filed April 19, 1883. Term of patent 3½ years.

To all whom it may concern:

Be it known that I, DAVID B. KERR, a citizen of the United States, residing at Philadelphia, in the county of Philadelphia and State 5 of Pennsylvania, have invented and produced a new and original Design for a Pattern to be wrought in Two-Ply Upholstery Tapestry or Damask, woven with two warps and two wefts in such colors as may be desired; and I 10 do hereby declare that the photographic print accompanying this specification conveys to any one skilled in the art of weaving upholstery tapestry and damask a clear understanding of the same, and is sufficient to enable such persons to use my invention.

What I claim as my invention, and desire to secure by Letters Patent, is—

The design for upholstery tapestry or damask, as shown in the photographic print accompanying this specification.

DAVID B. KERR.
